UNITED STATES PATENT OFFICE.

GEORGE N. HARTMAN, OF WATERTOWN, WISCONSIN.

NONTRANSFERABLE CHECK.

Application filed July 2, 1927. Serial No. 203,043.

This invention relates to improvements in non-transferable checks.

The object of this invention is to provide a simple, inexpensive form of check adapted to be used as a non-transferable badge or dance check and for analogous purposes and uses wherein the check is to be attached to a garment or supporting article in such a manner that it cannot be removed without destroying an integral portion thereof.

In the drawings:

Figure 1 is a view of a coat having my improved check applied thereto in a position for use.

15 Figure 2 is a view of one form of my improved check as it is customarily marketed.

Figure 3 is a similar view showing a modified construction.

20 Figure 4 is a view of the check shown in Figure 3 as it appears when the tape has been secured to the holder at both ends.

Figure 5 is a view showing a third modification in which an independent piece of tape may be applied.

25 Like parts are identified by the same reference characters throughout the several views.

A tape holder is employed which comprises a pair of discs 10 and 11, preferably made of paper, having gummed inner surfaces.

30 A piece of tape 12 may be inserted between the two discs or sheets of paper 10 and 11 as shown in Figure 2 and the surfaces gummed together upon and about the tape and throughout approximately one-half of the inner face of each disc.

The two discs may be left separated throughout their other half portions as clearly shown in Figure 2, and the tape 12 may have its opposite end en-

40 cased in a metallic sheathing 13. When it is desired to use the check, the tape is passed through a button hole or other suitable aperture in the article to which the check is to be applied and the extremity 13 turned backwardly in the direction of the discs 10 and 11 until a portion of the tape 12 can be passed

45 between the unsealed half portions and the latter gummed together to hold the tape in position as shown in Figure 1.

50 For greater security, the discs and the end portions of the tape 12 may be also secured together by eyelets 15 as shown in Figure 4.

In Figure 3, the tape 12 has one end portion permanently secured to the discs and the

discs permanently connected together at one 55 side by an eyelet 15, the other halves of the two discs being left unconnected preparatory to the insertion of the tape 12 between them, whereupon they will be gummed together. In Figure 5, I have illustrated two similar 60 discs, 10^a and 10^b which are integrally connected along a folding line 17. When these discs are folded, they may be used in the same manner as the discs 10 and 11, one end of a piece of tape such as the tape 12 being first 65 inserted between the two discs near the folding line and the other end inserted between the discs on the opposite side, whereupon the two discs or sheets will have their inner 70 surfaces gummed together in the same manner as illustrated in the other views.

While I have referred to the sheets 10 and 11 as discs, it will be understood that they may be of any suitable form and they may be composed of paper or any other suitable 75 material capable of having inner surfaces gummed or covered with adhesive material, whereupon the two sheets may be secured together. The tape 12 may comprise a band or string of any suitable material capable of 80 being engaged and securely held by the gummed surfaces of the sheets 10 and 11, or connected thereto by rivets or eyelets such as the eyelets 15.

I claim:

1. A non-transferable dance check having a body comprising two sheets of paper coated with adhesive one portion of each normally secured to a corresponding portion of the other, and another portion of each normally 90 unsecured, a tape portion having an end normally secured between the secured portion of the body sheets, and an unsecured end adapted to be secured between the unsecured portion of the body sheets when the same are 95 secured together by the said adhesive.

2. A non-transferable dance check having a body comprising two facing plies of paper, a tape having a portion of its length normally interposed between a portion of the opposed surfaces of said plies and adhesively secured therebetween, whereby the plies are secured in facing relation, said plies having free unfastened portions, at least one of said portions being coated with adhesive and said 100 tape having a free end adapted to be secured between the unfastened portions of said plies.

GEORGE N. HARTMAN.
